FLOOR-CLOTH WITH FASTENING MEANS

Xavier Burckle, Thann, France, assignor to Société dite: Filature et Tissage du Territoire, Thann, France, a company

Filed Dec. 22, 1958, Ser. No. 781,953

Claims priority, application France Dec. 23, 1957

4 Claims. (Cl. 15—247)

This invention relates in general to floor-cloths and has specific reference to an improved floor-cloth adapted on the one hand to be easily attached to a cleaning tool, for example a deck swilling brush, a squeegee or any other brush of this character, so as to be easily detachable therefrom, for example when it becomes necessary to rinse or wring the floor-cloth, and on the other hand to be re-fitted with the same facility on the brush for performing the cleaning work contemplated, the fastening device being so designed that it will not interfere with the rinsing and wringing of the floor-cloth when the latter is removed from the brush.

Another object of this invention consists in providing a floor-cloth having a fastening device secured permanently to one of its marginal portions and adapted to fit instantaneously on brushes of different types and sizes without appreciably increasing the sale price of the floor-cloth, this fastening device being applicable, if desired, to a floor-cloth of conventional type.

Finally, this invention is also concerned with a floor-cloth of the type broadly described hereinabove wherein the fastening device may last at least as long as the floor-cloth itself while remaining constantly safely attached thereto.

The devices proposed up to now in this field did not meet all the requirements set forth hereinabove.

According to this invention, a fastening device for securing a floor-cloth on a brush or the like may be manufactured economically by forming this fastening device as a single moulded unit of thermoplastic synthetic material having a certain elasticity. This unit is molded according to any adequate and known process and comprises an external ring-like portion formed with a radial slit opposite to a base portion formed integrally with said ring, said base portion being secured on the floor-cloth by injection while the ring-like portion lies externally of the floor-cloth. Thus, the ring portion may be opened to a considerable extent by moving the pair of ring-forming side arms on either side of the slit, away from each other whereby during this opening movement the two edges of the slit move in a direction at substantially right angles to the main plane of the ring. Thus, the ring may be either fitted on a stick of a floor brush or deck swilling brush or squeegee, in close vicinity of the brush portion thereof, without threading this ring throughout the stick length, or removed therefrom with the same facility by simply pulling on the floor-cloth.

It will be noted that the moulding of the fastening device and its fixation on the floor-cloth may be effected in a single injection-moulding operation by using a suitable plastic material and a conventional press.

A complementary feature of this invention is that the base portion by which the fastening member is secured on the cloth is moulded around the marginal portion of the floor-cloth which is thus embedded in the plastic material inside this base portion and forms an integral part of the fastening member. Preferably, the base

2

portion has an elongated shape so as to extend along a substantial length of the aforesaid marginal portion of the floor-cloth whereby the binding action will be effective on a considerable area and during the hot moulding step the plastic material will penetrate through the yarn of fibre interstices of the cloth to constitute an inseparable bond. Under these conditions the fastening member cannot be torn away from the floor cloth.

According to a particularly advantageous form of embodiment of this invention the fastening member has the general shape of a plate formed with a cavity corresponding to the ring aperture, and with other weight-reducing recesses at those places where the removal of material is not likely to interfere with the strength of the device.

Around the ring aperture the ring arms may comprise on either side of the plate a projecting rib whereby the inner cylindrical surface of the ring will be longer than the thickness of the plate, so that this ring will adhere with a maximum surface on the stick of the floor-brush or squeegee.

The binding base portion may be connected to the outer periphery of the ring portion by a pair of radially extending oblique arms.

In order to afford a clearer understanding of this invention and of the manner in which the same may be carried out in the practice, reference will now be made to the attached drawing forming part of this specification and illustrating diagrammatically by way of example a typical form of embodiment of this invention. In the drawing:

Figure 1 is a front view showing the marginal portion of the floor-cloth with the fastening device of this invention secured thereon, the ring portion being clearly visible in the upper portion of the figure;

Figure 2 is a section taken upon the line II—II of Fig. 1; and

Figure 3 is a side view showing the ring in the open position when fitting the device on a brush stick or removing same therefrom.

In the form of embodiment illustrated in the drawing, the floor-cloth of any conventional type is designated by the reference numeral 1 and the marginal portion thereof on which the device of this invention is secured is designated by the reference numeral 2.

The fastening device consisting of resilient thermoplastic material is moulded as an integral unit and has the general form of a plate with a base portion 3 connected to the periphery of the ring by arms 4, 5 extending obliquely relative to said base portion and radially relative to said ring, as shown. The ring is split radially at 6, that is, at a position diametrically opposite to the base portion, the reference numerals 7, 8 designating the resulting arms formed on either side of the slit 6. These arms have a T-shaped cross- or radial section as shown in Fig. 2, the wings of the T forming on the inner aperture side of the ring a pair of annular ribs 9, 10 projecting on either side of the plate faces, so that the inner surface of the ring extends on a length materially greater than the plate thickness. These ribs 9, 10 reinforce the region of the device which contacts the stick of the floor brush or squeegee without interfering with the torsional movements of the arms 7, 8 which are necessary for fitting the device on the stick and removing same therefrom.

As the injection step is carried out on the edge of the floor-cloth the thermoplastic material is moulded around the cloth edge and on its two sides, thus forming a coating 11 and thus this material will penetrate deeply into the interstices between the yarns or fibres of the cloth portion located within the coating 11 and this portion will be safely embedded in and welded to the plastic material. This coating 11 may be non-continuous and cloth por-

tions 12 of any suitable contour left in their bare condition are shown to this end in Fig. 1.

To open the ring, the operator simply moves the arms 7, 8 away from each other in opposite directions parallel to the ring axis as shown in Fig. 3, each arm being subjected in this case to a resilient torsional movement around the base of said ring. When the arms 7, 8 are released, the upper ends thereof are caused by the inherent resiliency of the material to resume their initial position in which they register with each other, and the ring will remain secured on the stick without any risk of accidental removal or loosening. In fact, a tractive effort transmitted from the stick to the floor-cloth through the intermediary of this ring will exert a moment substantially co-planar with the ring and the substantial width of the arms 7, 8 in this plane will prevent these arms from divaricating to an extent sufficient to separate the device from the stick. Consequently, the ring cannot open itself due to the sole action of the floor brush or squeegee on which it is fitted, irrespective of the movements accomplished by this stick.

Of course, various modifications as to the shape, proportions and material used for the practical embodiment of this device may be contemplated without departing however from the basic principle and features characterizing this invention as set forth in the appended claims.

I claim:

1. A floor-cloth with a fastening member permitting its mounting on a cleaning device, such as a floor brush or the like, comprising a floor-cloth, a fastening member consisting of a single, integral unit of synthetic thermo-

plastic resilient material having a base portion extending along a relatively long part of one edge of said floor-cloth, the threads of which are embedded into the material of said base, and a ring portion having an internal part extending axially and an external part extending radially, positioned externally of the said floor-cloth and split radially at a location opposite to said base portion.

5 2. A floor-cloth as claimed in claim 1, in which said fastening member has the general shape of a plate and 10 said base portion has openings into which extend threads of said floor-cloth thereby strengthening the connection of said floor-cloth to said fastening member.

15 3. A floor-cloth as claimed in claim 1, in which spaced radially directed oblique arms connect said base portion 15 of the fastening member to the periphery of said ring.

4. A floor-cloth as claimed in claim 1, wherein said internal part extending axially projects beyond said external part extending radially providing the ring portion 20 of said fastening member with a T-shaped section having an internal cylindrical surface which is materially greater than the thickness of said fastening member.
